UNITED STATES PATENT OFFICE.

JAMES C. THERIOT, OF TAFT, CALIFORNIA.

ADJUSTABLE JOURNAL-BOX.

1,219,192.

Specification of Letters Patent. Patented Mar. 13, 1917.

Application filed April 5, 1916. Serial No. 89,088.

To all whom it may concern:

Be it known that I, JAMES C. THERIOT, a citizen of the United States, residing at Taft, in the county of Kern and State of California, have invented certain new and useful Improvements in Adjustable Journal-Boxes; and I do hereby declare the following to be a full, clear, and exact description of the invention, such as will enable others skilled in the art to which it appertains to make and use the same.

This invention relates to improvements in adjustable journal boxes, and has for its primary object to provide simple and efficient means for effecting an accurate adjustment of the relatively movable bearing piece of a journal box.

Another object is the provision of a novel adjusting device for journal boxes of the type described and claimed in my pending application Serial No. 81,952, filed March 3, 1916, embodying a single wedge or taper key.

With these and other objects in view, the invention consists in the novel construction, combination and arrangement of parts as will be hereinafter specifically described, claimed and illustrated in the accompanying drawings, in which:

Figure 1 represents a fragmental side elevation, partly in section, of a well known type of journal box, illustrating the improved adjusting device applied thereto,

Fig. 2 represents a side elevation of the improved adjusting device removed,

Fig. 3 represents an edge elevation, partly in section,

Fig. 4 represents a fragmentary side elevation, partly in section, of a journal box, illustrating a modified type of the adjusting means applied thereto,

Fig. 5 represents a side elevation of the modified type of adjusting device removed, and

Fig. 6 represents a longitudinal sectional view on the line 6—6 of Fig. 5.

Referring to the drawings in detail, wherein similar reference numerals designate corresponding parts throughout the several views, the numeral 7 indicates a shank, preferably rectangular in cross section and provided with a pair of spaced lateral projections 8, arranged at and adjacent one end of the shank 7. The end of the shank opposite the projections 8 is rounded,

as indicated at 9, and formed with external screw threads.

A wedge or taper key 10 is arranged with one of the faces thereof in sliding engagement with the side face of the shank 7 opposite the projections 8, and the relatively large end of the wedge is reduced in width and directed angularly, as indicated at 11. The recess 12 between the angular end 11 and the shoulder 13 receives a nut 14, threaded upon the shank 9. The angular end 11 is formed with an opening 15 of such diameter as to slidably receive the screw threaded terminal 9 of the shank and permit longitudinal adjustment of the wedge 10 with relation thereto. An adjusting nut 16 is fitted upon the screw threaded terminal 9 of the shank and is engaged with the side of the angular end 11 of the wedge opposite the nut 14, and adapted to coact therewith to lock the wedge in adjusted position with relation to the shank 7. A lock nut 17 is fitted upon the shank and engaged with the adjusting nut 16 for locking the latter in adjusted position.

The adjusting device above described is particularly designed for use in connection with a connecting rod journal box of the type illustrated in Fig. 1, and which includes the connecting rod 18, U-shaped strap 19 rigidly connected with the head of the connecting rod 18 and the relatively stationary and adjustable bearing pieces 20 and 21, respectively. The parallel ends of the strap 19 are formed with the usual slots 22 in which is engaged the rectangular portion of the shank 7, the lateral projections 8 engaging the parallel members of the U-shaped strap and securing the shank in position. The wedge 10 is engaged with the relatively adjustable bearing piece 21 and is adapted to be moved longitudinally of the shank 7 by properly adjusting the several nuts 14, 16 and 17 to effect the desired adjustment of the bearing piece 21 with relation to the bearing piece 20.

Referring to the modification of the invention illustrated in Figs. 4 to 6, the numeral 25 indicates the shank of the adjusting device which is preferably rectangular in cross section and provided at one end with a cylindrical head 26. The portion of the shank 25 opposite the head 26 is rounded and formed with external screw threads 26a on which is fitted an internally 110

screw threaded nut or clamping plate 27, adapted to co-act with the head 26 in securing the shank in position in the journal box.

- 5 A wedge or taper key 28 is engaged with one side face of the rectangular shank 25 and the clamping plate 27 and the relatively large end thereof is reduced in width, directed angularly and apertured, as indicated at 29, to slidably receive the screw 10 threaded portion 26^a of the shank. Adjusting nuts 30 and 31 are fitted upon the screw threaded portion of the shank and are engaged with the opposite sides of the angularly directed portion 29 of the wedge 28 15 to effect the desired adjustment of the latter with relation to the shank 25. A lock nut 32 is fitted upon the shank 25 and is engaged with the outer adjusting nut 30 for locking the latter in adjusted position.
- 20 In applying the type of adjusting device illustrated in Figs. 4, 5 and 6 to a journal box, the shank 25 is inserted through the slots 22^a in the strap 19^a and is secured in position by adjusting the plate or nut 27, 25 so as to draw the latter and the head 26 in firm engagement with the parallel portions of the strap 19^a. The wedge 28 is subsequently adjusted by means of the several nuts 30, 31 and 32, so as to effect the desired adjustment of the relatively adjustable bearing piece 21^a with relation to the stationary bearing piece 20^a.

What I claim is:

1. In an adjustable journal box, a shank 35 having one end screw threaded, a wedge slidably engaged with said shank and having an angular apertured end slidably receiving the screw threaded portion of said

shank and a recess adjacent the angular end, and adjusting nuts fitted on the screw threaded terminal of said shank and engaged on the opposite sides of the angular terminal of said wedge and one of said nuts being confined between one side wall of the recess and the angular terminal of 40 said wedge, said nuts constituting adjustable means for rigidly securing the wedge against longitudinal movement in either direction upon the shank.

2. In an adjustable journal box, a shank having one end screw threaded, a head at the opposite end of said shank, a clamping plate adjustably fitted on the threaded end of said shank, a wedge slidably engaged with said shank having an angular apertured end and a recess adjacent the angular end, and adjusting nuts fitted on said shank and engaged upon opposite sides of said angular end, one of said nuts being confined between the angular end of said wedge 55 and the opposite side wall of said recess.

3. In an adjustable journal box, a shank having one end screw threaded, a head at the opposite end of said shank, a clamping plate adjustably fitted on the threaded end of said shank, a wedge slidably engaged with one side of said shank, and means for adjusting said wedge longitudinally of said shank.

In testimony whereof I affix my signature 70 in presence of two witnesses.

JAMES C. THERIOT.
